(57) **CLAIM**

The ornamental design for a beverage container lid, as shown and described.

DESCRIPTION

FIG. 1 is a perspective view of a beverage container lid in an open position according to the present invention, with portions shown in broken lines, and therefore, not constituting part of the claimed design;

FIG. 2 is a front view thereof, with a pull tab shown in broken lines, and therefore, not constituting part of the claimed design;

FIG. 3 is a rear view thereof;

FIG. 4 is a right side view thereof, with the pull tab shown in broken lines, and therefore, not constituting part of the claimed design;

FIG. 5 is a left side view thereof, with the pull tab shown in broken lines, and therefore, not constituting part of the claimed design;

FIG. 6 is a top view thereof, with portions shown in broken lines, and therefore, not constituting part of the claimed design; and,

FIG. 7 is a top view of an alternative embodiment of a beverage container lid in a closed position according to the present invention, with portions shown in broken lines, and therefore, not constituting part of the claimed design.

All broken lines in the above figures are for illustrative purposes only and form no part of the claimed design.
